UNITED STATES PATENT OFFICE

MICHAEL IANNONE, OF ROCHESTER, NEW YORK

DESIGN FOR A BOILER HEATER

Application filed May 19, 1933. Serial No. 48,165. Term of patent 7 years.

To all whom it may concern:

Be it known that I, MICHAEL IANNONE, a citizen of the United States, and a resident of Rochester, county of Monroe, and State of New York, have invented a new, original, and ornamental Design for a Boiler Heater, of which the following is a specification, reference being had to the accompanying drawing, forming a part hereof.

Fig. 1 is a front elevation of a boiler heater embodying my new design.

Fig. 2 is a side view of same.

Fig. 3 is another side view of same.

I claim:

The ornamental design for a boiler heater substantially as shown.

MICHAEL IANNONE.
